CLAIM

The ornamental design for a squeeze station support, as shown and described.

DESCRIPTION

FIG. 1 is a top, front, left side perspective view of a squeeze station support showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a bottom, rear, right side perspective view thereof; and,

FIG. 9 is a front view showing three squeeze pumps of the squeeze station support in the state of storage and drainage. The broken lines show features of the squeeze station support that form no part of the claimed design.

1 Claim, 9 Drawing Sheets
